UNITED STATES PATENT OFFICE.

SIEGMUND LOEWE, OF BERLIN, GERMANY, ASSIGNOR TO WESTERN ELECTRIC COMPANY, INCORPORATED, OF NEW YORK, N. Y., A CORPORATION OF NEW YORK.

SYSTEM FOR GENERATING OSCILLATIONS.

Application filed March 19, 1921, Serial No. 453,841, and in Germany April 19, 1918.

(GRANTED UNDER THE PROVISIONS OF THE ACT OF MARCH 3, 1921, 41 STAT. L., 1313.)

This invention relates to oscillation generators, using electron discharge tubes having a plurality of electrodes. An object of the invention is to provide an oscillation generator, oscillating directly into an antenna or other load circuit of variable impedance so arranged that variations of the antenna or load impedance have a very small effect on the frequency of oscillation.

10 In other words the oscillation generator is so arranged that the frequency of the output current is substantially independent of said output current or variations in the impedance of the output circuit. This is accomplished by providing an anode, which constitutes the anode for an auxiliary oscillating circuit, but also functions as a grid with respect to a principal anode connected to the main oscillation circuit.

20 The invention also comprises novel electrode arrangements adapted to be utilized in tubes for carrying out the invention. From one aspect, the system herein described, may be regarded as an oscillation generator connected to an amplifier which amplifies the generated oscillations, the oscillation generator and the amplifier being combined in one vacuum tube and having a common cathode. The output circuit of 25 the oscillation generator may be treated as the input circuit of the amplifier.

The generation of undamped electrical oscillations by vacuum tubes becomes more difficult in proportion as the antenna is more 30 strongly damped. At the same time the total efficiency of the oscillation generation is greatly decreased. The present invention deals with an apparatus which will avoid this condition. The cause of this condition 35 was recognized to be the comparatively inefficient operation of the grid of the vacuum tube in the common arrangement. The basic idea of the invention is the use of a means for increasing the grid effect beyond that 40 caused by the feed back.

45 Fig. 1 shows a space discharge oscillator embodying the invention. Fig. 2 represents a modified arrangement of the electrodes of the space discharge tube. Fig. 3 shows another arrangement of the space discharge tube electrodes. Fig. 4 shows a different form of oscillation generating system embodying the invention.

In Fig. 1, a vacuum tube or space cur-

rent device 1 includes an incandescent cathode 2, grid or control element 3, anode 4 and auxiliary anode 5. The circuit includes the anode battery 6, the antenna 7 with means for tuning, 8. The antenna or load circuit and the anode or output circuit are coupled by the coil 9. The grid 3 is excited by the auxiliary anode or output circuit 10 which may include the resonant circuit 11 and thereby induce a potential upon the grid by means of the input circuit including the coil 12. A part of the chief anode battery may serve with advantage as the battery of the auxiliary anode circuit, but the heating battery or a special source of voltage may also be used for this purpose. If the anode 5 source is not constant, but an alternating current machine, a transformer may be used, so that the voltage of the auxiliary anode circuit can even be chosen larger than that of the chief anode circuit.

75 The method of operation is as follows:

Oscillations of the frequency determined by the resonant frequency of the tuned circuit 11 are generated in the auxiliary anode circuit 10 in the usual manner by means of 80 the anode battery 6 and the feed back 12.

On account of the arrangement of the oscillation generator with respect to the main output circuit, the tuning of circuit 11 is independent of variations in the impedance of the main output circuit. The grid variations thus produced naturally act also on the real anode circuit consisting of the anode 4, coil 9, and source of voltage 6; a high frequency current flows in this circuit 85 and has the same period as that of the auxiliary anode circuit. The antenna is now coupled with the main anode circuit and set in resonance with the frequency generated in the auxiliary anode circuit. It is vital 90 that the auxiliary anode system and the grid coil should be made as free from damping as possible, since it is important because of the dissipation to generate the highest possible grid variations with the least 95 possible energy.

100 The auxiliary anode system can always be chosen with a view to the greatest possible grid effect, that is with circuit 11 as free as possible from damping and transformation to high grid potential. Hence great fluctuations also occur in the main anode circuit and strongly excite the antenna.

It is advisable to arrange the auxiliary anode inside the main anode as shown in Fig. 2. The auxiliary anode can itself be constructed as a grid and can act as such for the main anode. (cf. Fig. 3).

If the present method is combined with an ordinary circuit for the generation of oscillations, pure undamped oscillations will be obtained when the main and auxiliary anode circuit are in resonance with each other, and a beat transmitter will be obtained when the two circuits are slightly out of resonance.

The application of this is shown in Fig. 4. A feed back with the antenna is formed by means of coil 13. If the antenna is slightly out of resonance with respect to circuit 11, beats are obtained.

What is claimed is:

1. Means for generating oscillations including a space current device having electrodes, an output circuit having a direct current conductive connection to electrodes of said device, and means including said device for transmitting oscillations to said output circuit from said generating means at a frequency substantially independent of current in said output circuit.

2. Means for generating oscillations including a space current device having electrodes, an output circuit having a direct current conductive connection to electrodes of said device, and means including said device, responsive to oscillations in said generating means, for transmitting said oscillations to said output circuit at a frequency substantially independent of current in said output circuit.

3. Means for generating oscillations including a space current device having a plurality of electrodes, and output circuit associated with said device, and means including a direct current conductive connection between said circuit and one of said electrodes for transmitting oscillations to said output circuit at a frequency substantially independent of current in said output circuit.

4. Means for generating oscillations including a space current device having a plurality of electrodes, a variable load circuit directly connected to said device, and means including one of said electrodes for transmitting oscillations to said output circuit at a frequency substantially independent of variations in said load circuit.

5. Means for generating oscillations including a space current device having a plurality of electrodes, a load circuit containing a variable impedance element directly connected to said device, and means including one of said electrodes for transmitting oscillations to said load circuit at a frequency substantially independent of variations in said impedance element.

6. Means for generating oscillations in-

cluding a space current device having a plurality of electrodes, a load circuit including an antenna, a transformer, said transformer being directly connected to electrodes of said device and to said antenna, and means including one of said electrodes for transmitting oscillations to said load circuit at a frequency substantially independent of variations in the impedance of said antenna.

7. An oscillation generator comprising a space discharge tube including a plurality of anodes and a common cathode, means for producing continuous discharges in a plurality of space paths between said cathode and said anodes; a control electrode adapted to control the discharges in a plurality of said paths, associated reactive networks for producing self sustained oscillations in one space path, and a work circuit connected to the other space path.

8. In an oscillation generator, a space discharge tube including a cathode, control electrode and a plurality of anodes, means for causing said control electrode to vary the impedance of the space paths between said cathode and both of said anodes, and an output circuit having a direct current conductive connection to an anode, whereby variations of impedance of said circuit are prevented from affecting the frequency of oscillations.

9. In an oscillation generator, a space discharge tube including a cathode, control electrode and a plurality of anodes, an oscillatory circuit connected to said cathode and one anode, a load circuit connected to said cathode and a second anode, said control electrode being adapted to independently control the space discharge between said cathode and said first mentioned anode, said first mentioned anode and said control electrode being adapted to jointly control the discharge to said second anode.

10. A space current device having an anode, cathode, and a control element, an input circuit connected to said control element, and a tuned output circuit connecting said anode to said cathode to transmit current in response to oscillations in said input circuit, said input and output circuits being coupled together, a second anode for said cathode, and a variable output circuit connecting said cathode to said second anode to transmit current in response to oscillations in said first mentioned output circuit, the tuning of said first mentioned output circuit, the tuning of said first mentioned output circuit being substantially independent of variations in said second output circuit.

11. A space current device having an anode, a cathode, and a control element, an input circuit connected to said control element, and an output circuit connecting said anode to said cathode to transmit current in response to oscillations in said input circuit,

said input and output circuits being coupled together, a second anode for said cathode, said second anode comprising portions located on opposite sides of said first anode, and a second output circuit connecting said cathode to said second anode to transmit current in response to oscillations in said first mentioned output circuit.

12. In combination, a space current device, a load circuit including a damped antenna having direct current conductive connection to said device, and means including said device for generating oscillations unaffected by the damping of said antenna.

13. A circuit comprising a space discharge device, a cathode therein, two cold anodes therein, an external circuit connected to said cathode and one of said anodes, a load circuit coupled to said external circuit, another external circuit connected to said cathode and the other of said anodes, an

input circuit and a feed-back coupling from said last named external circuit to said input circuit, said first named external circuit being free of material external electromagnetic or electrostatic coupling to said input circuit. 25

14. A circuit comprising a space discharge device having a cathode and two anodes, an input circuit, one of said anodes being included in an external circuit, means in said circuit to transfer waves to a load circuit, and the other of said anodes being included in another external circuit and means in said last named circuit functioning 30 essentially to transfer waves to an input circuit of said device. 35

In witness whereof, I hereunto subscribe my name this ninth day of February, A. D., 1921.

DR. SIEGMUND LOEWE.
